Patented Nov. 9, 1971

222,577

ELECTRICAL KEY

Alfiero F. Balzano, Sunland, Calif., assignor to
R. B. Phinizy, Anaheim, Calif.

Original design application Dec. 12, 1969, Ser. No. 20,484,
now Patent No. 220,557, dated Apr. 20, 1971. Divided
and this application Aug. 5, 1970, Ser. No. 24,322

Term of patent 14 years

Int. Cl. D8—06

U.S. Cl. D8—136

FIG. 1 is a front perspective view of an electrical key showing my new design; and

FIG. 2 is a rear perspective view thereof.

This application is a division of my co-pending application D-20,484, filed Dec. 12, 1969, now patented (D-220,557, Apr. 20, 1971).

I claim:

The ornamental design for an electrical key, substantially as shown.
